UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,212,812.

Specification of Letters Patent. Patented Jan. 16, 1917.

Application filed July 21, 1914. Serial No. 852,253.

To all whom it may concern:

Be it known that I, WILLIAM J. ROCHE, a resident of Meadville, in the county of Crawford and State of Pennsylvania, have invented a new and useful Improvement in Garment-Stays, of which the following is a specification.

This invention relates to garment stays, and particularly to wire garment stays for 10 use in corsets and other like articles of wearing apparel.

The object of the invention is to provide an improved stay of the character described which can be readily manufactured, which 15 has material resistance to bending strains, which is resilient, which has a long length of wire in a stay of given dimensions, and which is not liable to take a permanent set when subjected to short bends. And 20 more particularly it is designed to provide a stay composed of a plurality of wires, intertwined along the middle portion of the stay, and having return loops in each wire on the edge of the stay.

25 The invention comprises the stay herein-after described and claimed.

In the drawings, Figure 1 represents a plan view on an exaggerated scale of one face of a stay embodying the invention; and 30 Fig. 2 is a similar view of a modified form of the stay.

The stay shown in the drawings is formed of wire, and preferably is formed of a plurality of wires. Any suitable number of 35 wires may be used but the stay shown comprises only two wires 1, each of which is bent back and forth from edge to edge of the stay to form a series of alternately disposed loops or eyes 2 lying along the edges of the 40 stay and connected by transversely extending crossing portions 3. The edge loops may be of any suitable form, but preferably are bent back upon themselves toward one end and toward the center line of the stay, so 45 that they are in effect returned loops. The two wires 1 of which the stay is formed are intertwined or interwoven, so that the crossing portions 3 of the two wires cross each other intermediate the edges of the stay, 50 which securely fastens the two wires together and produces mutual support therebetween. In the arrangement shown the wires are so arranged that the loops or eyes 2 along the edges of the stay are opposite each

other transversely of the length of the stay, 55 so that they are in effect arranged in pairs of oppositely disposed loops. These loops may, if desired, extend nearly to the next adjacent crossing portion of the wire, which is a crossing portion of the other wire of 60 the stay, as shown in Fig. 1, or, if desired, each loop may somewhat overlap the next adjacent crossing portion of the other wire of the stay, as shown at 5, Fig. 2, thereby reinforcing the edges of the stay and giving 65 it increased resistance to bending strains.

The stay described is simple, can be readily manufactured and contains a long length of wire in a stay of given dimensions, so that wear is distributed over a long length of 70 wire and there is no liability of the stay taking a permanent set when subjected to short bends. Also, the stay is very resilient and is particularly resistant to flexure in the edgewise direction, so that it is suitable for 75 special uses in which edgewise flexure is not desired.

What I claim is:—

1. A garment stay, comprising a plurality of wires bent back and forth in opposite directions in zigzag form to form a series of return loops lying along the edges of the stay and extending toward its middle line and transversely extending crossing portions connecting said loops, the return loops 80 on the edges of the stay being disposed in pairs opposite each other.

2. A garment stay, comprising a plurality of wires bent back and forth in opposite directions to form a series of edge loops and 90 crossing portions, the edge loops being returned toward the center line of the stay and the wires being intertwined with each other.

3. A garment stay, comprising a plurality of wires bent back and forth in opposite directions to form a series of return loops lying along the edges of the stay and transversely extending crossing portions, the return loops on the edges of the stay being 95 disposed in pairs opposite each other, all of 100 said loops also extending toward the same end of the stay.

In testimony whereof, I have hereunto set my hand.

WILLIAM J. ROCHE.
